OTTO LEOPOLD, OF WERNIGERODE, HARZ, GERMANY

SOUND RECORDING AND REPRODUCING APPARATUS

Application filed April 4, 1931, Serial No. 527,716, and in Germany April 8, 1930.

This invention relates to a sound recording and reproducing apparatus, in which the sound conductor is guided in straight direction so that the talking range of the records is considerably increased as compared with the hitherto used tone arms oscillating in an arc. Moreover portions of the records can be listened to, so that the stylus can be lifted off the record and then again placed in the same tone groove, from which it has been removed. Zinc foils, metal foils, celluloid foils and the like are employed for recording the sound, the stylus standing perpendicular to the foil. If it is desired to listen to records of a different kind, the tone conductor is accordingly shifted back with the parts connected thereto, in order to enable the inclined adjustment of the stylus in the manner customary therefor.

An embodiment of the invention is illustrated by way of example in the accompanying drawings in which:

Fig. 1 shows an apparatus in top plan view.

Fig. 2 is a front elevation of the apparatus.

Fig. 3 shows a roller guide in side elevation.

Fig. 4 is a side view of the apparatus.

Fig. 5 is a side view of the device for lifting the stylus off the record.

Fig. 6 illustrates a detail.

A movable tone-arm 2 shifts backwards and forwards in a stationary tone conductor 1. On this arm a short inclined tone-arm 3 is fitted, which carries a sound box 4, which in the case of self recording and reproducing of sounds stands perpendicularly above the imaginary line 6 extending through the centre of the turn table 5 (Fig. 1) and is guided straight in the direction of this line. The shifting of the movable tone-arm 2 in the tone conductor 1 is effected by rollers 7 and 8, the roller 8, on which the tone arm 2 rests, being constructed as shown in Fig. 3. The rollers 7 and 8 are mounted in points 9 so that they turn easily.

The rollers 7, 8 are carried by bows 10, 10' the inner bow 10 being fixed on the tone conductor 1, whereas the outer bow 10' is fixed on an angle iron 11 fixed by screws to a slot guide 12. A similar slot guide 12 is pro-

vided for the vertical supporting arm 13 of the tone arm (Figs. 1 and 2). The bows 10 and 10' form the bearings for a screw spindle 14, which is driven from a clockwork, electric motor or the like by bevel wheels 31 and 32. The spindle transmission is 1:2, that is the spindle rotates once, whilst in the same period of time the record rotates twice on the turn table 5.

A sleeve-shaped ring 15 is fixed on the tone arm 2 and a bolt 16 extends therethrough (Fig. 5), an adjusting nut 17 being screwed on the upper end of this bolt and an eccentric 18 mounted on the lower end of the bolt and bearing against a half nut 19 (Fig. 6), fixed by a blade spring 20 (Fig. 5) to the ring 15. When it is desired to record, the eccentric 18 must be so adjusted that the screw threads of the half nut 19 engage in the screw threads of the spindle 14. The spindle then guides the vertical diamond stylus 21 (Fig. 4) of the sound box 4 on the plate so that the stylus can cut closely juxtaposed spiral grooves into this plate. During the reproduction the half nut is lifted off the spindle (Fig. 5).

Behind the upper guide rollers 7 a shaft 23 is journaled in two brackets 22, a hand lever 24 being fixed to one end of said shaft. On short arms 25, extending from the shaft 23, a sleeve 26 is mounted which during the sound reproduction assumes the position indicated in Fig. 4, bearing on a rearwardly projecting arm 27 of the sleeve 15. When it is desired to hear a record portion wise, the lever 24 is lowered in the direction of the arrow shown in Fig. 4, the sleeve 15 thereby moving downwards the arm 27 so that the sound box 4 is raised to enable the stylus to disengage from the spirals of the record, which continues to rotate. If the lever is returned into the position shown in Fig. 4, the stylus engages exactly at the point at which it was removed. In order to prevent an automatic lifting of the sound box, a locking disc 28 is mounted on the shaft 23 with which in the locking position a resilient pawl 29 engages (Fig. 4) which bears on the locking disc in the raised position (Fig. 5).

The new device can be employed also for the reproduction of all kinds of records,

which have not been recorded by the owner of the apparatus. In this instance the tone conductor must be shifted 15 mms. towards the rear with the parts connected thereto, so

5 that the stylus of the sound box can be set at an incline in the usual manner, whereas in the case of self recording and reproduction the stylus stands perpendicular. In both instances the line along which the stylus travels

10 must pass through the centre of the record. In order to effect the shifting the fixing screws are loosened, with which the parts 11 and 13 are fixed on the carriage guides 12, 12', and the parts 11 and 13 are then shifted 15

15 mms. so that the screw holes 30 (Figs. 1 and 4) are utilized as fixing points.

I claim:

1. In a sound recording and reproducing apparatus the combination composed of a

20 stationary tone conductor and a movable tone arm forming together a tone guide, said tone arm shiftable in straight direction in said tone conductor, an inclined tone arm connected to said movable tone arm, a sound box

25 carried by said inclined tone arm, rollers mounted in points adapted to guide said movable tone arm, a sleeve fixed on said movable tone arm, a bolt extending through said sleeve and said movable tone arm, an

30 adjusting disc on the upper end of said bolt, an eccentric on the lower end of said bolt, a half nut bearing against said eccentric, a blade spring connecting said half nut to said sleeve, and a screw spindle controlling said

35 sound box adapted to engage said half nut during the recording.

2. A sound recording apparatus, comprising in combination a tone guide, a movable tone arm of said guide, a shaft behind and

40 above said movable tone arm, a ring-shaped sleeve carried by said arm, a sleeve on said movable tone arm, a rearwardly projecting arm of said ring-shaped sleeve adapted to support said sleeve on said shaft, a hand lever

45 on said shaft adapted to rotate said sleeve for lifting the stylus off the record, a screw spindle, a half nut resiliently connected to said ring-shaped sleeve adapted to engage said screw spindle and to be disengaged by said

50 lever, when a record has to be played portion wise, carriage guides, a bracket carrying said tone guide shiftable in one of said carriage guides, and a bracket carrying said movable tone arm, said shaft and said screw spindle

55 adapted to be shifted back and fixed in the second of said carriage guides for reproducing records.

In testimony whereof I affix my signature.
OTTO LEOPOLD.
